STOCKING

William Tait, Wyomissing, Pa., assignor to Millway Knitting Mill, Inc., Millway, Pa., a corporation of Pennsylvania

Application June 3, 1950, Serial No. 10,322

Term of patent 14 years

(Cl. D47—7)

To all whom it may concern:

Be it known that I, William Tait, a citizen of the United States, residing at Wyomissing, Pennsylvania, have invented a new, original, and ornamental Design for Stockings, of which the following is a specification, reference being had to the accompanying drawing forming a part hereof.

Fig. 1 is a side view of a stocking showing my design.

Fig. 2 is a fragmentary, rear perspective view of the same.

I claim:

The ornamental design for a stocking, as shown.

WILLIAM TAIT.
